UNITED STATES PATENT OFFICE.

WILLIAM DALTON, OF SCHENECTADY, NEW YORK.

MANUFACTURE OF BLENDED POWDER COMPOUNDS.

1,204,137.

Specification of Letters Patent. Patented Nov. 7, 1916.

Application filed July 18, 1916. Serial No. 109,888.

To all whom it may concern:

Be it known that I, WILLIAM DALTON, of Schenectady, in the county of Schenectady and State of New York, have invented a certain new and useful Improvement in the Manufacture of Blended Powder Compounds, of which improvement the following is a specification.

My invention relates to the manufacture of compounds comprising a plurality of powdered ingredients, more particularly powder used in explosive projectiles, and its object is to provide a method or process of treatment of the ingredients, and a mechanism, whereby a plurality of very thin and uniform layers of finely divided powder particles may be deposited, as they are sifted from receptacles inclosing proportioned quantities of the powder, in such manner as to obtain a high degree of perfection and thoroughness in blending, by a rapid and a simple method; to prevent the escape of dust in the process of manufacture; and to guard against danger to the operator when the combined ingredients form an explosive compound.

The improvement claimed is hereinafter fully set forth.

In the accompanying drawings: Figure 1 is a view, partly in elevation and partly in vertical central section, of a powder blending machine adapted for the practice of the process of my invention; Fig. 2, a plan view thereof; Fig. 3, a similar view, with the cover removed, and a portion broken away to show a mercury seal formed around the discharge outlet of the machine; Fig. 4, an enlarged sectional detail view of the mercury seal and discharge outlet; Fig. 5, a view, in elevation, and on a smaller scale, of a dust collector and exhaust fan; Fig. 6, an enlarged view, in elevation, of a powder shipping can and sifter and a receptacle formed thereon; Fig. 7, a plan view thereof, partly in section; and, Fig. 8, a partial vertical section, on the line *a—a* of Fig. 2, showing the application of a liquid spraying device.

In the practice of my invention, referring descriptively to its application in the manufacture of powder compounds which can be mechanically acted on with safety, when taking the usual precautions employed in the manufacture of ordinary explosive compounds, a plurality of the required

site dry powdered ingredients is selected in the proper proportions to form the desired blend or compound. The several proportions of ingredients are placed in separate receptacles, from each of which they are sifted to a common movable supporting surface, at rates of delivery corresponding to the predetermined proportions of the several ingredients required to form the blend or compound desired. By the movement of the supporting surface, the particles of the several proportions of ingredients are caused to be deposited thereon in thin intimately commingled layers, which are broken up and discharged, and the resulting properly proportioned mixture is thereafter repeatedly relayered, so as to obtain the practically complete and intimate commingling of the particles of the several ingredients in the powdered compound.

When blending powdered ingredients which, after having been combined, form a highly sensitive explosive compound in their dry state, special precautions are necessary to avoid destructive explosions. Heretofore, it has been the practice to protect the operator by means of a substantially built metallic shield, formed around a mechanically or hand operated mixer. To further guard against danger, the moving parts of the mixer, and the receptacle walls which came in contact with the compound, were covered by a protecting shield of suitable materials, adapted to avoid undue percussion and friction. Compounds of the character referred to, are, when dry, so extremely sensitive as to be liable to explode when slid down an inclined surface.

In order to completely guard against danger, and to avoid the slightest mechanical mixing of a sensitive explosive compound, in the practice of the process of my invention, each of the several proportions of dry powdered ingredients is, as before described, placed in a separate receptacle, and while the proportions of ingredients are being sifted from the receptacles to a common movable supporting surface, they are, before being combined into an explosive compound, sprayed with a liquid, as water or alcohol, for the purpose of thoroughly saturating them with liquid and forming a non-explosive plastic mixture, which can be safely molded into any desired form.

Referring descriptively to the specific structural embodiment of the mechanism of my invention which is herein exemplified, I provide a frame, 1, which may be of any preferred form, but is preferably, as shown, made triangular, for the purpose of conveniently fastening three symmetrically disposed pivotal bearings, 2^a, each adapted to support a conical roller, 2. A circular flanged track, 3, is adapted to bear upon the rollers, and to rotate about its center when driven by a belt, 3^a, from any suitable source of power. The upper surface of the track is secured to a movable powder supporting surface, which is formed by the conical bottom, 4^a, of an otherwise cylindrical hopper, 4, which is supported on and rotated with the track. An annular water seal trough, 4^b, is formed on the periphery of the hopper. A cover, 5, is supported on three frame posts, 1^a, and is provided with a downwardly projecting circular flange, 5^a, which dips into the water contained in the annular seal trough, for the purpose of preventing any outward flow of dust from the rotary hopper. Two circular and downwardly projecting flanges, 5^b and 5^c, are formed on the cover, 5, and are disposed one on the inside and the other on the outside of the hopper rim, to prevent powder from being splashed into the annular seal trough, 4^b.

The hopper is provided with a discharge outlet, 4^d, which is centrally disposed at the lower extremity of the conical bottom, 4^a. This outlet is manually controlled by a valve, 6, by actuating a lever, 6^a, coupled to the valve, or a rod, 6^b, connected thereto for convenience when desiring to operate the valve from below the floor, 7, upon which the machine is mounted.

A mercury dust seal is formed in a removable stationary annular trough, 16, which is supported by the notched ring, 17. Three radially disposed braces, 17^a, are formed on said ring, and are fastened to the frame, 1, thereby securely positioning the ring concentrically with respect to the outlet, 4^d, and the downwardly projecting circular flange, 4^c, so as to cause the flange, 4^c, to dip into mercury contained in the annular trough, 16, and thereby form an effective seal against the escape of powder. The trough, 16, can be removed by turning it until the lugs, 16^a, register with the notches, 16^b. A cloth bag, 18, or other suitable transferring means, is attached to the trough, 16, for the purpose of connecting the discharge outlet with a supplementary blending apparatus, 19, to a powder can, 20, or other receptacle which may be provided. The supplementary blending apparatus comprises a plurality of inclined chutes and means for vibrating them, and, as it is not claimed as of my invention, it is not, in detail, herein described. The receptacle or can, 20, is pref-

erably supported upon a weighing scale, 20^a, and is removably connected to the apparatus by a cloth hose, 21, which is provided with a hose coupling, 21^a, of ordinary construction, for fastening it to the can.

A plurality of inlet ports, 8, formed in the cover, 5, is disposed adjacent to the inner side of the rim of the hopper, 4, and the cover flange, 5^a. A cylindrical powder receptacle, 11, is mounted above each of these ports, said receptacles being supported by a plurality of U-formed spring bolts, 12, which are secured to the cover by nuts, 12^a. A screen, 11^a, forms the bottom of each receptacle, and is fastened in the usual manner. A vibrator, 13, is attached to each screen, for the purpose of sifting powder from the receptacle, 11, into the rotatory hopper. A cloth shield, 11^b, is attached to the lower end of each receptacle, and to the cover, 5, and serves to close an annular opening in the cover around the receptacle, to prevent the escape of dust from the hopper.

The conical bottom, 4^a, of the hopper, is preferably inclined at an angle which is not sufficiently great to cause sliding of the powder downward toward the outlet when the valve, 6, is closed, in order that a great number of very thin layers of powder may be deposited on the bottom, as the powder is sifted from the several receptacles, 11, by the vibrators.

A radially disposed powder scraper, 22, is located within the hopper, and is hinged, near its middle, to the lower extremity of a lever arm, 23, which is pivotally supported upon the flange, 5^a, by the hinge pin, 5^a, so as to permit the scraper to be raised and lowered, by means of the notched segmental handle, 23^a, which protrudes through the upper side of the cover, 5.

A large central cleaning opening, 9, is formed in the cover, and is closed by a removable lid, 9^a, having an opening which is connected to a dust collecting fan, 10, by a conduit, 10^a. A dust separating device, 10^b, of ordinary construction, is interposed between the fan and the hopper, for the purpose of trapping and wetting all the powder dust which may be drawn from the hopper. A dust collecting cloth, 9^a, is stretched across and fastened to the bottom of the lid, 9^a, so as to prevent an excess of dust from passing upward into the fan.

Powder may be emptied into each of the receptacles, 11, from a powder can, 24, by means of a vibrator, 25, which is secured to a can clamp ring, 26. The clamp ring is fastened to the open end of a commercial powder can, by a clamp screw, 26^a, and is provided with a flange, 26^b, for the purpose of loosely embracing the top of the receptacle, 11, thereby holding the can loosely in position while resting on top of the receptacle, and when powder is being vibrated

from the can by admitting air to the vibrator, 25, through the hose, 25^a, from any convenient source of supply.

One or more liquid spraying nozzles, 31, are connected by a pipe, 31^a, to any suitable source of supply, and are disposed above the movable powder supporting surface formed by the conical hopper bottom, 4^a, so as to completely spray all the surfaces forming the interior walls of the hopper while it is being rotated, and to thoroughly wet the ingredients while they are being sifted and deposited in layers upon the movable supporting surface. The stop valve, 31^b, is provided for starting and stopping the sprays, which are operated only when blending highly sensitive explosive compounds, during which operation the supplementary blending apparatus, 19, is removed.

In the operation of the machine on powders which can be mechanically mixed with safety, when taking the usual precautions followed when blending ordinary explosive powders, carefully determined proportions of the different powders intended to form the blend desired, are supplied from powder cans into any desired number of the receptacles, 11, by means of the can clamp, 26, and the vibrator, 25, which is provided with a sufficient length of air hose, 25^a, to permit it to be placed over any one of the receptacles. After filling all, or any desired number, of the receptacles with a properly proportioned amount of powder, calculated to give the desired blend, the scraper, 22, is lifted to its uppermost position, the hopper is rotated, and the vibrators, 13, are started simultaneously as nearly as possible, and each is adjusted to sift at the desired rate, for the purpose of depositing a great number of uniformly thin layers of powder upon the conical hopper bottom. When the receptacles are emptied, the vibrators, 13, are stopped, and the vibrator, 19^a, on the supplementary blender, 19, is started. By lowering the scraper, 22, continued rotation of the hopper will cause the layered powder, the upper surface of which is indicated by the reference symbol, 30, in Fig. 1, to be thoroughly broken up and mixed before lifting the valve, 6, to permit its downward flow into the bag, 18, from which it is fed into the supplementary blender, 19, in which the properly proportioned mixture is repeatedly relayered. From this blender it passes down into the can, 20, and is weighed by the scale, 20^a.

When operating the machine on highly sensitive explosive compounds, as, for example, percussion compounds, the method, above described, of filling the receptacles, 11, and sifting their contents into the hopper, is followed. In addition thereto, the stop valve, 31, of the liquid supply pipe, is opened, so as to simultaneously and thor-

oughly spray and wet the powdered ingredients as they are being deposited upon the moving supporting surface, 4^a. After completing the layering and spraying operation, the scraper, 22, is lowered and the wet compound is scraped from the hopper, through the outlet, 4^b, after opening the valve, 6, the supplementary blender, 19, having been previously removed.

I claim as my invention and desire to secure by Letters Patent:

1. The process of manufacture of blended powder compounds which consists in separately sifting a plurality of properly proportioned dry powdered ingredients upon a moving supporting surface, so as to deposit the powdered particles of the ingredients thereon, in successive pluralities of thin and intimately mixed layers of each of the several ingredients; thereafter breaking up the multiple layered deposit; and finally repeatedly relayering said deposit, so as to thoroughly blend the entire mixture.

2. The process of manufacture of blended powder compounds which consists in separately sifting and depositing a plurality of dry powdered ingredients upon a moving surface, and simultaneously spraying the ingredients with a liquid as they are being layered upon the moving surface, for the purpose of intimately and safely combining the ingredients without dangerous mechanical manipulation, and thoroughly saturating them with liquid, thereby forming a non-explosive mixture which can be safely molded into any desired form.

3. The combination, in a powder blending machine, of a frame; a rotary hopper supported thereon, and having a discharge outlet; a hopper cover; means for sifting powder into the hopper; and a liquid seal formed between the cover and the hopper to prevent undesired escape of powder therefrom.

4. The combination, in a powder blending machine, of a frame; a rotary hopper supported thereon, and having a discharge outlet; a hopper cover; means for sifting powder into the hopper; a stationary member formed around the discharge outlet; and a liquid seal formed on said member and around the outlet to prevent undesired escape of powder from said outlet.

5. The combination, in a powder blending machine, of a frame; a rotary hopper supported thereon, and having a discharge outlet; a hopper cover; means for sifting powder into the hopper; an annular trough formed around the hopper and adapted to contain a sealing liquid; and a downwardly projecting circular flange fastened to the cover and extending into the trough for the purpose of forming a seal with the liquid therein.

6. The combination, in a powder blending

machine, of a frame; a rotary hopper supported thereon, and having a discharge outlet; a hopper cover; means for sifting powder into the hopper; an annular trough 5 formed around the hopper and adapted to contain a sealing liquid; a downwardly projecting circular flange fastened to the cover and extending into the trough for the purpose of forming a seal with liquid therein; 10 and a shield disposed adjacent to the trough for preventing powder from being splashed thereinto.

7. The combination, in a powder blending

Copies of this patent may be obtained for five cents each, by addressing the "Commissioner of Patents, Washington, D. C."

machine, of a frame; a rotary hopper supported thereon; a multiported hopper cover; 15 powder sifting receptacles disposed above the ports of the cover; a powder shipping can; and a portable vibrating means adapted to be attached thereto for the purpose of emptying the can into one of said sifting 20 receptacles.

WILLIAM DALTON.
